PLASTIC COATED SHEET MATERIAL

Richard A. Mazur, McFarland, Wis., assignor to United States Rubber Company, New York, N.Y., a corporation of New Jersey

Filed Aug. 9, 1965, Ser. No. 86,512

Term of patent 14 years

(Cl. D87—3)

FIG. 1 is a plan view of a plastic coated sheet material, showing my new design, and

FIG. 2 is a cross section taken along the line 2—2 of FIG. 1.

A single repeat of the design is enclosed within the quadrangle, bounded by the broken lines in FIG. 1, through which the section line 2—2 is drawn.

I claim:

The ornamental design for a plastic coated sheet material, as shown and described.
